M. H. SHOENBERG ET AL

ELECTRICAL CIGAR LIGHTER

Filed Aug. 9, 1926

UNITED STATES PATENT OFFICE.

MILTON H. SHOENBERG AND LESTER SCHON, OF SAN FRANCISCO, CALIFORNIA; SAID SCHON ASSIGNOR TO SAID SHOENBERG.

ELECTRICAL CIGAR LIGHTER.

Application filed August 9, 1926. Serial No. 128,066.

This invention relates generally to electrical devices for lighting cigars or cigarettes.

It is an object of this invention to devise a cigar lighter which will be simple in construction and convenient to operate.

It is a further object of this invention to provide an improved form of heating unit which may be readily removed from a cigar lighter for replacement.

10 It is a further object of this invention to simplify and improve the mounting for the control switch of a cigar lighter and to facilitate insulating the same.

15 It is a further object of this invention to devise a single insulating member for mounting both the control switch elements and the heating element of a cigar lighter.

20 Further objects of this invention will appear from the following description in which we have set forth the preferred embodiment of our invention. It is to be understood that the scope of the invention is to be determined from the appended claims and the state of the prior art.

25 Referring to the drawings:

Figure 1 is a cross sectional elevational view of a cigar lighter constructed in accordance with this invention.

30 Fig. 2 is a transverse cross sectional view taken along the line 2—2 of Fig. 1.

Fig. 3 is a cross sectional view taken along the line 3—3 of Fig. 1.

Fig. 4 is a cross sectional view taken along the line 4—4 of Fig. 1.

35 Fig. 5 is a cross sectional view taken along the line 5—5 of Fig. 1.

Fig. 6 is a diagrammatic view illustrating the manner in which the resistance wires are connected to the heating unit terminals.

40 Fig. 7 is a cross sectional view taken along the line 7—7 of Fig. 2.

The invention comprises generally a body member 10 upon the upper end of which is mounted a heating element 11. The body member has been shown as comprising a lower flanged base portion 12 and an upper cup-shaped shell 13, the base portion being connected to the shell by means of a hollow stem portion 14. While it is obvious that these parts may be made partially or entirely integral, they are preferably constructed as separate elements and permanently secured together during the process of manufacture. Thus for example, the base

portion 12 and shell 13 may be constructed 55 of pressed sheet metal while the stem portion 14 may be formed of tubular material. The upper and lower ends of the stem portion are provided with rolled over portions 16 and 17 for engaging the adjacent ends 60 of the shell 13 and base portion 12 respectively.

In order to mount the heating unit 11 upon the cup-shaped shell 13 there is provided a disc 19 of suitable insulating material such as mica, which has its periphery secured to the upper rim of the cup 13. The heating element is preferably mounted centrally of this disc 19 so that the disc forms a shelf surrounding the element. As the diameter of the shell 13 is substantially larger than the diameter of the heating element 11 this shelf will prevent the heating element from coming into direct contact with a supporting surface in case the lighter is 75 tipped over on one side, and forms a convenient means for catching ashes which may drop from the heating element when the lighter is in use.

The heating element 11 has been constructed so that it may be removed from the lighter as a unit without the necessity of disconnecting wires or removing screws or bolts. Thus this element has been shown as comprising a core 20 of suitable refractory 85 material having the intermediate portion of its periphery grooved to receive a suitable resistance wire 21. This resistance wire is preferably coiled so as to increase its length and effective resistance. In order to minimize direct transfer of heat from the resistance wire to the core by convection and thus permit the wire to rapidly attain a glowing temperature, the core is preferably provided with a plurality of longitudinal 90 grooves 22 so that the resistance wire contacts with the core only at spaced points about the core periphery. One end of the core is provided with an extension 23 which is fitted within a metal sleeve 24. This sleeve 100 is provided with an externally threaded portion 26 which may be of lesser diameter than that portion of the sleeve fitting over the extension 23. Centrally of the core there is provided a rod or bolt 27 having its lower end projecting through the sleeve 24. The head 28 of this bolt preferably serves to retain the sleeve 24 upon the core 20 and for

this purpose there is provided a suitable washer or bushing 29 of insulating material such as porcelain, which bushing serves to clamp against the inturned flange 30 provided upon the lower end of the sleeve 24. A nut 33 is threaded upon the other end of the rod 27 to facilitate assembly of the parts.

With this heating element it is proposed to employ the sleeve 24 and the bolt 27 as 10 terminal connectors for the ends of the resistance wire. Since the resistance wire 21 is of very small diameter it would be difficult to connect its ends directly to the bolt 27 and sleeve 24. Means have therefore 15 been provided to facilitate this connection and also to insure a low temperature and non-oxidizing electrical contact. Thus, as indicated in Fig. 6, adjacent the last convolution of the upper end of the resistance 20 wire another wire 35 of substantially larger diameter is looped around the core and has its ends twisted together with the adjacent end of the resistance wire to form a stranded conductor 36 which is then brought beneath 25 the nut 33 and securely clamped to the adjacent plate of the core 20. Similarly adjacent the lower turns of the resistance wire there is looped a wire 37 having its ends twisted together with the adjacent ends of 30 the resistance wire to form a stranded conductor 38 which is extended downwardly in one of the grooves 22. The sleeve 24 is formed with pressed-in portions 39 corresponding generally to the grooves 22 upon 35 the core so that when the sleeve is forced over the core extension 23 it serves to securely grip the stranded conductor 38 and thus make positive electrical contact with the resistance wire. The stranded conductors 36 and 38 are not only more convenient 40 to attach to the bolt 27 and sleeve 24 respectively, but serve to conduct away the heat of the resistance wire and thus lower the temperature of the wire at points where it makes electrical contact.

With a resistance wire of this kind the heating element would soon become injured if cigars or cigarettes were permitted to come directly into contact with the wire. 50 To obviate this difficulty there has been provided a guard 41 preferably constructed of metal which is slipped over the core 20 and is provided with perforations 42 to permit direct radiation of heat. To retain the inner walls of this metal guard out of contact with the resistance wire 21 the core has been shown as provided with a plurality of upper and lower spaced projections 43 and 44. A piece of insulating material 46 may 55 also be inserted between the upper end of the guard 41 and the adjacent end of the core 20 in order to prevent short circuiting of the bolt 27 upon the guard. This guard is preferably fixed with respect to the core 60 20 as by means of a ring 47 having a pressed

fit with the lower end of the guard, this ring being provided with a tongue 48 interlocking with one of the grooves 22. A cigar or cigarette placed in contact with the guard 41 is subjected to direct radiation of heat 70 from the resistance wire 21 and also to heated air drawn into the cigar or cigarette which must first pass over the heated wire.

Both the means for mounting the heating element and the switch for controlling the 75 current supplied thereto are preferably secured directly to the insulating disc 19. Thus secured to the inner face of the disc in position to register with a central aperture in the same, there is provided a metal ring 80 member 50 which is internally threaded to engage the threaded portion of the sleeve 24. Thus for example, the member 50 may be retained upon the disc 19 by means of integral tabs 51 which are clinched through 85 apertures provided in the disc. To make contact with the bolt 27 there is provided a metal spring contact strip 52 which is adapted to bridge across the center of the disc and is retained thereto by means of an 90 integral strip 53 which is likewise provided with clinched tabs 54. To prevent short circuiting of the contact strip 52 with the ring member 50 the free end of this strip is provided with an up-turned portion 56 95 which abuts against the lower face of the disc 19. The switch means includes a spring metal strip 57 which forms a movable switch contact and is formed as an integral extension of the strip 58. Similar to the strip 100 53, the strip 58 is provided with clinched tabs 59 for engaging the insulating disc 19. The free end of the strip 57 is manually 105 movable by means of a push button 60 which slidably extends through one side of the 110 shell 13. Extending from the member 50 into proximity with the free end of the strip 57 there is a stationary contact element 61 with which the movable strip 57 is adapted to be brought into electrical contact upon pressing inward upon the push 115 button 60. If the push button is made of metal it is preferable to insulate it from the strip 57 as by means of an insulating pin 62 secured to the inner end of the button.

The insulating disc 19 is secured to the upper edge of the shell 13 by suitable means such as a metal ring 66 provided with a rolled outer edge engaging struck out portions 67 provided upon the shell 13. In 120 order to cover over the various metal parts which are exposed to the upper face of the disc 19 a second insulating disc 68 may be placed over the disc 19 and clamped to the same by means of the ring 66. Relative rotation between the disc 19 and the shell 13 is prevented by means of an inturned projection 69 provided upon the shell 13 which is adapted to engage within a slot provided in the periphery of the disc. The inner sur- 130

face of the shell 13 is also preferably insulated by means of a strip or ring 70 of suitable insulating material.

From the above description it will be apparent that electrical connections to the heating element may be established merely by screwing the element into the internally threaded ring 50. The electrical conductors 63 may be threaded through the hollow stem 14 and brought out through the bottom of the base member 12 or through an aperture 64 in one side thereof. The ends of the conductors are connected to the strips 53 and 58 whereby the switch comprising the movable strip 57 and the stationary contact 61, is placed in series with the heating element. Therefore upon closing this switch by pushing the button 60 the resistance wire is quickly heated to incandescence to light a cigar or cigarette. For convenience the other ends of the conductors may be provided with a suitable electrical plug 65 for attachment to any standard socket or receptacle.

Because the shell 13 together with the disc 19 forms a shelf surrounding the lower portion of the heating element, there is no danger of starting a fire in case the lighter becomes upset after it has been in use. For example, the dot and dash line 71 indicates the position which the lighter would take in upset position with respect to a plane supporting surface, thus showing that in this upset position the heating element would be a substantial distance away from any inflammable material. The switch also opens itself upon release of the push button so that there is no possibility of the device

remaining connected to the line after being in use. To aid in retaining the device in upright position the base portion 12 has been shown as provided with a weight in the form of a washer 72 which is retained within the base by means of a rolled edge portion 73. The lower face of this washer is covered over by means of a suitable cushioning material 74.

We claim:

1. In a cigar lighter, a heating element comprising a refractory core, a resistance wire wound upon said core, and means for mounting the core and making electrical connections to the resistance wire comprising a metal sleeve secured to one end of the core, a bolt extending centrally through the core and serving to retain the sleeve upon the core, and means for electrically connecting said sleeve and bolt to the ends of said resistance wire. 50
2. In a lighter of the class described, an elongated refractory core having parallel ribs spaced circumferentially about its periphery, a resistance wire wound upon said core, a cylindrical metal guard surrounding said core and wire and mounted upon the core, said guard having side walls lying adjacent to but spaced from said wires, said guard having its side walls perforated whereby air drawn thru any side of the guard will be heated by contact with said core and wire. 60 65 70

In testimony whereof, we have hereunto set our hands.

MILTON H. SHOENBERG.
LESTER SCHON.
